UNITED STATES PATENT OFFICE.

WILLIAM WRIGHT, OF CHICAGO, ILLINOIS, ASSIGNOR TO E. PAYSON SMITH, OF SPRINGFIELD, ILLINOIS.

BRAKE-GEAR MOUNTING.

Application filed April 10, 1926. Serial No 101,157.

My invention relates to a brake gear housing and method of mounting the same to the underframe members of a car and more particularly for use in connection with a 5 gondola type especially intended as a coal or ore car and provided with sliding bottom doors, whereby the load is dumped from the car toward opposite sides of the track.

The invention has for its object the provision of a gear housing so constructed as to permit attachment to one side or member of the center sill of the car underframe and also to one of the slide rails of the car bottom sections or doors; the invention, as previously stated, being especially intended for use on cars of the type referred to wherein the brake-staff is mounted at the end of car body and extends through an extension or platform on the car underframe and 20 therefore at a distance rearward of the end sill of the car underframe, thus necessitating attachment of the gear housing to other elements of the car underframe, without in any way interfering with said elements or 25 any movable parts carried thereby.

The construction and its advantages will be readily comprehended from the following detailed description, wherein—

Figure 1 is a plan view with portions of 30 the car underframe members and showing the gear housing mounted in place.

Figure 2 is a side elevation, with certain portions of the bottom door slide-rail in section.

Figure 3 is a perspective view of the bottom casting or member of the gear housing.

Figure 4 is a perspective view of the top casting or member looking at the bottom thereof.

Figure 5 is an end elevation illustrating the housing attached to one member of the center sill and a portion of a slide-rail adjacent to the end of the car.

Figure 6 is a vertical cross sectional view 45 of the gear housing.

My invention, as illustrated in the drawings, contemplates a two piece housing composed of the top member or casting 15, see Figure 4, and the bottom member or casting 16, see Figure 3.

The top member or casting 15, at least in so far as the main body portion thereof is concerned, is preferably more or less of triangular formation, with the three angles 55 or junctures of the respective longitudinal

sides or margins terminating in downwardly disposed legs 17, 18 and 19, see Figure 4. The legs 17, 18 and 19 are shown flanged along their vertical edges as shown at 20; the flanges 20 being preferably also continued throughout the marginal edges of the main body portion of the casting or member 15, thereby not only reenforcing the entire casting or member 15, but the flanges 20 on the various legs also provide means for reenforcing the connections between the top casting or member 15 and the bottom member or casting 16. The bottom member 16 is provided with upstanding portions or ends 21, 23 and 22, adapted to lap the inner sides of the legs 17, 18 and 19 and be riveted or otherwise secured thereto. The legs of both castings or members are shown provided with apertures for the reception of rivets or other fastening means.

The top member or casting 15 is shown provided with suitable openings 24 and 25; the former being intended to receive the lower end of the brake-staff 26; while the opening 25 is intended to receive the 70 trunnion or hub of the driven gear.

The top plate or member 15 on one of the edges thereof, namely on the side intermediate of the legs 17 and 18, is provided with an extension or plate 27 of more or less 85 width and length; the plate 27 being horizontally disposed and arranged in a plane slightly above the plane of the top member or casting 15, with which it is formed integral by means of suitable upwardly and 90 outwardly extending reenforcing flanges or webs 28 arranged along the ends and at spaced intervals beneath the bottom of the plate as shown in Figure 4. The plate 27 is shown apertured at 29 in order to permit 95 it to be fastened or riveted to the lower flange or bottom of the center sill member 30, as shown at 31, thereby securing the top plate in proper place, see Figure 5. With the plate or extension 27 disposed toward one 100 side of the main portion of the top member or casting 15, the gear housing will be disposed toward one side of the center-sill and provide proper clearance for operation of the brake-staff and other elements of the 105 gear mechanism.

The top member or casting 15 on the marginal side intermediate of the legs 17 and 19 is provided with a lobe or extension 32, see Figure 1, which is adapted to be dis- 110

posed beneath the laterally disposed flange of the bottom slide-rail 33 of the car frame; that is to say, the lobe or extension 32 is intended to be secured to one of the door 5 slide-rails at the end of the car bottom; the lobe or extension being shown riveted at 34 to the end rail, see Figures 1, 2 and 5.

The bottom 16 consists of a tripartite casting or ramiform plate having the three 10 ramifications or arms 35, 36 and 37. The arm or portion 35 is shown provided with a countersunk aperture 38 intended to be aligned with the opening 24 in the top member 15 for reception of the brake-staff 26 and 15 hub of the drive gear. The opening 38 in the bottom member is countersunk as mentioned to provide a seat 39 for the trunnion or hub 40 of the drive gear 41 of the brake mechanism, see Figures 2 and 6. The hub or 20 trunnion of the drive gear 41, which extends to opposite sides thereof, has the upper end disposed in the opening 24 in the top member 15, while the lower end of the hub is preferably flanged inwardly at 42 to provide 25 a seat for the lower end of the brake-staff 26, whose immediate end 43 is reduced for passage through the reduced opening in the lower end of the trunnion or hub of the drive gear and through the opening in the 30 bottom member 16. The bottom member 16 is also provided with an opening 44 for reception of the extended hub portion 45 of the driven gear 46. The upper side of the gear 46 is provided with a small hub or trunnion 35 which extends into the opening 25 of the top member 15. The extended lower hub portion 45 of the driven gear 46, throughout most of its length, may be squared to provide driving 40 relation with the spool or chain drum 47 in order that the latter will be caused to rotate with the driven gear 46; the spool or drum, which seats on the lower member 16, will maintain the driven elements in proper position.

45 As will be more clearly seen in Figures 2 and 6, the arm or portion 35 of the lower member 16 preferably extends into a horizontal plane above that of the other part of the member so as to maintain the drive gear 41 in proper position and thus obviate the necessity for employing spacing elements. The bottom member 16 is preferably provided with a vertically disposed reenforcing rib or web 48 arranged to extend throughout the 55 length of the arms of the lower member 16; reenforcing webs or ribs being preferably arranged along the marginal edges of the member to give it strength and rigidity.

60 The chain of the brake-operating mechanism, which is suitably anchored or secured to the spool or drum 47, passes through the

open side of the housing intermediate of the arms or portions 36 and 37 of the lower member and therefore intermediate of the legs 18 and 19 of the upper member, so that the 65 pull or strain will be parallel with the point of attachment 34 to the bottom slide rail, while the wide bearing and attachment by means of plate 27 to the center sill will provide a very rigid mounting capable of withstanding the strains to which it normally is subjected.

The invention has been disclosed in what is believed to be the simplest embodiment 75 thereof and has been described in terms employed merely as terms of description and not as terms of limitation as modifications are possible without, however, departing from the spirit of my invention.

What I claim is:

1. In a brake gear mounting, the combination of a center sill member, and a bottom door slide-rail, with a gear housing composed of a three-sided top plate having depending legs at the junctures of the marginal edges, 85 an integral center sill engaging portion disposed laterally from a marginal edge of the top plate and arranged in a horizontal plane thereabove, an extension disposed laterally from another marginal edge of the top plate 90 for attachment to said slide-rail, and a Y-shaped bottom plate for supporting the gear elements, the ends of the arms of the bottom plate extending upwardly and secured to the depending legs of the top plate, one arm of the bottom plate having the driving portion 95 of the gearing journaled thereon while the driven portion of the gearing is journaled at the juncture of two arms of the bottom plate.

2. A brake gear mounting comprising a triangulated top plate provided with downwardly disposed flanged legs at the three corners, a horizontal portion integral with and disposed laterally beyond and lengthwise 105 of the long marginal side and in a plane above the plate, with a lug extending laterally from an opposite marginal edge, and a tripartite bottom plate adapted to rotatably hold the gear elements in place, the three 110 ends of said plate being disposed upwardly in lapping relation with the legs of the top plate, between the flanges thereof, and secured to said legs, one end of the bottom plate being disposed in a plane above that 115 of the other ends and having a socketed seat for the drive elements, while the bottom plate intermediate of the other two ends is adapted to receive the driven elements, said bottom plate having vertically disposed ribs 120 extending along the bottom thereof.

WILLIAM WRIGHT.
